UNITED STATES PATENT OFFICE.

JOHN T. WELLS, OF NEWPORT, KENTUCKY, ASSIGNOR TO THE EDWARDS MANUFACTURING COMPANY, OF CINCINNATI, OHIO, A CORPORATION OF OHIO.

MOVING-PICTURE-FILM-PRINTING UNIT.

1,210,743.

Specification of Letters Patent.

Patented Jan. 2, 1917.

Original application filed October 5, 1914, Serial No. 865,129. Divided and this application filed February 12, 1915. Serial No. 7,841.

To all whom it may concern:

Be it known that I, JOHN T. WELLS, a citizen of the United States, and residing at Newport, in the county of Campbell and 5 State of Kentucky, have invented a new and useful Improvement in Moving-Picture-Film-Printing Units, of which the following specification is a full disclosure.

My invention relates to mechanism adapting a unit of a moving picture taking and projecting machine to be used for printing the film.

The general features are shown in Patent No. 1,165,146, granted to me, December 21, 15 1915.

The object of the invention is to provide the unit shown and described in my said patent, with means adapted to printing requirements, enabling the same fundamental 20 mechanism to be used serially for the three steps of taking, printing and projecting, with the fewest possible interchangeable parts and operations.

The features of the invention are more 25 fully set forth in the description of the accompanying drawings, forming a part of this specification, in which:—

Figure 1 is a vertical section through the center of the film and light controlling mechanism. Fig. 2 is a similar section of the 30 upper portion of the back plate and adjacent parts, showing the printing plate in place. Fig. 3 is a perspective view of the printing plate.

The machine illustrated in the drawings 35 is of a type adapted when inclosed in a camera-box, for use as a picture taking camera, and is also adapted to be used as a film printing machine. When the film and light controlling mechanism is removed from the 40 camera-box and used in coöperation with a projecting lantern, a complete projecting machine is obtained.

It will, of course, be apparent that my 45 proved printing plate may be applied to other types of film controlling units of the same general character.

The mechanism shown consists of a front-board 20, a base-board 21 and a lining-plate 22, to which side frames 24, supporting the film feeding mechanism, are secured. 50 A vertically adjustable focal tube plate 35 is slidably mounted in the front-board 20 near the lining plate 22 and carries a focal

tube 36, which projects rearwardly through 55 an elongated aperture in said plate and terminates with a framing plate 37. The light shutter operates adjacent the front end of the focal tube.

The film guide plate 38 (see Fig. 1) is of 60 an elongated double S formation, having an intermediate straight portion provided with an elongated opening or film light exposure aperture 39, in which is disposed the framing-plate 37, mounted on the inner end of 65 focal-tube 36. This guide plate is secured to the lining-plate 22 and serves as a support for other parts, as will be described.

The film in its travel through the machine is first engaged by a constantly driven 70 feed roller 42, which serves to replenish the film loop 43 initially manually formed, during the threading of the film into the machine. The film is next intermittently fed through the guide channels and past the 75 focal exposure tube, by an intermittently operated roller 44. The constantly driven roller 45 serves as a "take-up" roller and between said roller and the roller 44 is another initially manually formed film loop 80 46. These film loops relieve the film of any excessive feeding strains and by reason thereof an even tension of the film past the focal plane is obtained.

For holding the film in contact with the 85 feed roller, I provide a tension device consisting of a pair of rubber surfaced rollers 75, carried by a housing 76. Said housing is provided with studs 77, which project through orifices in the upper end of the 90 guide plate 38, and is forced toward the feed roller by springs 79 surrounding said studs between the housing and guide plate. The upper edge of the housing 76 is elongated and formed into a film chute to guide the 95 film in true alinement to the feed roller.

Duplicate tension devices 80, 81, are provided for the intermittent feed roller 44 and the "take-up" roller 45. These are carried by a back-plate 82, which is removably pivoted near the bottoms of the side frames and is held in position by a bail 83, engaging its upper edge. By raising said bail the back plate 82 may be swung backward, as shown in dotted lines, Fig. 1, to permit the threading of the film into the machine. The back-plate 82 is provided with a light aperture 84 for admitting the light rays of a projecting

lantern to the film when the machine is used as a projecting machine.

The entire mechanism is driven by any suitable means such as an electric or other 5 motor or manually by an operating crank handle.

In the printing of the positive film, the developed negative and a sensitized film are simultaneously fed through the machine past 10 the framing-plate 37, the negative being next to said plate. To yieldingly hold said films in close contact and to provide a backing therefor, I provide a detachable printing plate 130, (see Figs. 2 and 3), formed 15 of spring sheet metal and provided with hook ends adapted to engage the top and bottom edges of the light aperture 84, in the back plate 82. The printed film, (which is a positive) is then developed, after which 20 it may be used in any standard projecting machine.

Having described my invention, I claim:—

1. In a device of the class described, an apertured film guide, film feed rolls for mov-

ing the film over said guide, a correspondingly apertured member hinged to open and close vertically relative to said guide, film feed rolls on said hinged member coacting with the first-named film rolls, and a detachable tension plate for closing the aperture of the hinged member and adapted to hold two films in close contact adjacent said guide aperture for printing. 25

2. In a device of the class described, the combination of a fixed and a hinged film 30 guide between which the film is fed, said guides having coincident focal apertures, a detachable film-tension plate for closing the aperture in the hinged guide member constituting a printing-back and means for intermittently advancing the film. 35

In witness whereof, I hereunto subscribe my name, as attested by the two subscribing witnesses.

JOHN T. WELLS.
